[57] CLAIM

The ornamental design for a chop saw, as shown and described.

DESCRIPTION

FIG. 1 is a perspective view of a chop saw, constituting a first embodiment of my new design;
FIG. 2 is a right elevational view of the first embodiment;
FIG. 3 is a left elevational view of the first embodiment;
FIG. 4 is a front elevational view of the first embodiment;
FIG. 5 is a rear elevation view of the first embodiment;
FIG. 6 is a top plan view of the first embodiment;
FIG. 7 is a perspective view of a chop saw with a blade installed thereon and constituting a second embodiment of my new design;
FIG. 8 is a right elevational view of the second embodiment;
FIG. 9 is a left elevational view of the second embodiment; and
FIG. 10 is a front elevational view of the second embodiment.
